(57) **CLAIM**

The ornamental design for a printer, as shown and described.

DESCRIPTION

FIG. 1 is a front, top, and left side perspective view of a first embodiment of a printer showing our new design;
FIG. 2 is a rear, top, and right side perspective view thereof;
FIG. 3 is a front view thereof;
FIG. 4 is a rear view thereof;
FIG. 5 is a top plan view thereof;
FIG. 6 is a bottom plan view thereof;
FIG. 7 is a right side view thereof;
FIG. 8 is a left side view thereof;
FIG. 9 is a front, top, and left side perspective view of a second embodiment of the printer;
FIG. 10 is a rear, top, and right side perspective view thereof;
FIG. 11 is a front view thereof;
FIG. 12 is a rear view thereof;
FIG. 13 is a top plan view thereof;
FIG. 14 is a bottom plan view thereof;
FIG. 15 is a right side view thereof; and,
FIG. 16 is a left side view thereof.

The broken lines illustrate portions of the printer and form no part of the claimed design.

1 Claim, 16 Drawing Sheets
